ARTHUR H. ADAMS, OF YONKERS, NEW YORK, ASSIGNEE TO TROY LAUNDRY MACHINERY COMPANY, INC., OF NEW YORK, N. Y., A CORPORATION OF DELAWARE

SPRING PAD

Original application filed October 20, 1928, Serial No. 313,858. Divided and this application filed October 1, 1929. Serial No. 396,591.

This application is a division of my co-pending application No. 313,858, filed October 20, 1928.

This invention relates to springs and also to methods and apparatus for winding convoluted springs. More particularly, the invention is concerned with springs of the type having inclined convolutions.

The invention is in the nature of an improvement upon the invention disclosed in the copending applications of Arthur H. Adams, Serial No. 245,180 and has for one of its objects to produce a closely wound skewed spring which has a maximum of resiliency in a direction perpendicular to the axis of the spring convolutions.

As described in said applications, the characteristics of skewed springs render them particularly advantageous in providing a resilient surface which is capable of localized compression without permanent deformation, such surfaces, for example, being employed in laundry machines, paper machines and the like. Accordingly, another object of the invention is to produce a resilient padding of the type disclosed in application Serial No. 245,180, in which the resilient element consists of a skewed convoluted spring which has a maximum of transverse resiliency for a given size of spring convolution.

A further feature is to provide a resiliently padded roll or the like employing as a resilient element thereof skewed springs having square or rectangular shaped convolutions.

Another feature pertains to the means for uniting the free ends of a coiled spring which is wrapped around a roll or other equivalent surface.

As is well known, laundry rolls, etc. are provided with one or more outer coverings of woven fabric with one end fastened to the roll and the other end free. In the case of rolls having a resilient padding formed of coiled springs wrapped around the roll such as disclosed in application Serial No. 245,180, it is important that the covering be fastened so that during the rotation the winding effect on the covering will not produce ridges in the spring padding. Accordingly a still further feature pertains to the novel method and

means for anchoring the roll covering or coverings whereby the tautness and the continuous winding effects thereof do not cause any appreciable unevenness in the surface of the spring padding proper. Other features and advantages not specifically enumerated will be apparent after a consideration of the following detailed description and the appended claims.

For the purpose of illustrating one preferred manner of using a spring according to the invention the same will be disclosed as applied to a laundry ironing roll, but it will be understood that this is merely for the purpose of illustration and that its applicability for analogous uses in other fields is within the scope of the invention.

Referring to the drawing, Fig. 1 shows in schematic form the successive steps to be followed in winding a square or rectangular convoluted and nested spring according to the invention.

Fig. 2 is a top plan view of the spring as it is formed according to the method illustrated in Fig. 1.

Fig. 3 is a top view of the spring, looking in the direction of the planes of the convolutions, and showing the alternate short and long loop structure of the top surface of a spring of this construction.

Fig. 4 is a bottom plan view of the spring, looking in the direction of the planes of the convolutions, and showing the staggered equal loop structure of the bottom surface of a spring of this construction.

Fig. 5 is a side elevation of a portion of a spring, according to the invention, with the convolutions spaced or stretched apart.

Fig. 6 is a top plan view of the spring of Fig. 5.

Fig. 7 is a bottom plan view of the spring of Fig. 5.

Fig. 8 is a view showing a portion of a laundry roll equipped with layers of fabric coverings which are spaced apart from the roll proper by a spring according to Figs. 5, 6 and 7. This figure also illustrates one preferred manner of locking the spring against creeping over the roll surface.

Fig. 9 illustrates a preferred manner of

securing the end of a fabric covering to the roll.

Fig. 10 is an end view of the cover anchoring means of Fig. 9 and also shows the manner of uniting the free ends of one of the spring members by caps.

Fig. 11 is a sectional view of the spring capping means shown in Fig. 10 showing the "pinched-in" character of the cap.

10 Fig. 12 is a simplified diagram showing the method of attaching a plurality of separate layers of fabric coverings at diametrically opposite points using the anchoring means of Fig. 9.

15 Referring particularly to Fig. 1, there is diagrammatically shown a method of forming an inclined square or rectangular spring with successive convolutions of different sizes so that each small convolution may nest within the adjacent large convolutions. The nesting effect enables the convolutions to be closer together than has heretofore been found possible and without curtailing the resiliency when the convolutions are subjected to pressure in a direction transverse to their common axis. This feature is important when such a spring acts as a resilient supporting surface such as is used in laundry rolls or the like since it provides a non-absorbent resilient support for the fabric covering and also presents a substantially continuous support therefor. As shown in Fig. 1, a length of spring wire of the requisite cross section and preferably of non-corrosive material such as phosphor-bronze, or the like, is subdivided into eight smaller lengths and each length is bent substantially at right angles with respect to the preceding length. In the case of a square spring the lengths 1, 2 and 5 are equal, while lengths 4 and 8 are shorter, preferably an amount corresponding to the thickness of the spring wire. Lengths 1, 2, 3 and 4 are then bent so that they normally lie at right angles with each other, thus forming a rectangular convolution and the purpose of making the length 1 shorter than length 3 is to give the convolutions of the completed spring an inclination as described in application Serial No. 284,722. The succeeding convolution comprises the lengths 5, 6, 7 and 8. As will be seen, length 6 is shorter than the corresponding length 2 of the larger convolution, so that the convolutions 5, 6, 7, 8 may, when the spring is in use, enter or nest within the convolutions 1, 2, 3, 4. The length 7, it will be understood, is the same as the corresponding length 3 of the large convolution. However, during the transverse compression of the spring the length 7 is inclined sufficiently to enable length 6 to fit below the corresponding length 2 of the convolutions 1, 2, 3, 4. The foregoing described cycle of bending at predetermined lengths is repeated throughout the rest of the spring wire, resulting in a structure, as shown

in Fig. 2, in which the successive convolutions are adjacent to each other but are progressively displaced along a common axis represented by the dot dash line 2-2. Fig. 2 represents a top plan view of the spring as it is formed. Fig. 3 is a top view of the spring looking in the direction of the plane of the convolutions and showing the alternate short and long loop structure of the top surface. Fig. 4 is a bottom plan view of the spring looking in the direction of the plane of the convolutions showing the staggered equal loop structure of the bottom surface. In order to use the spring shown in Figs. 2, 3 and 4 as a resilient supporting element, such, for example, as employed in laundry rolls, the spring is stretched until the turns thereof assume the desired spacing, for example, as shown in Figs. 5, 6 and 7. When the spring of Fig. 2 is thus stretched, in side elevation, all the convolutions appear to be of the same height, as shown in Fig. 5. However, when such a spring is locally compressed in the direction of the arrow the small convolutions are distorted and the upper ends fit within the left-hand adjacent large convolutions. This action will be clearer when considered in connection with Fig. 6, which shows a top plan view of the spring of Fig. 5. As shown in this figure, the length 6 of each small convolution is such that when the spring is compressed it will freely enter below the corresponding length 2 of the left-hand adjacent large convolution. Fig. 7 illustrates the relation between the bottom lengths of successive large and small convolutions. From a consideration of Figs. 5, 6 and 7, it will be seen that in the normal position of the spring the height of all the convolutions is substantially the same and in this respect the spring is similar to the inclined spring shown in application Serial No. 284,722. It is to be noted however, that the transverse resiliency of the spring in this latter application is limited by the fact that during transverse compression each convolution piles up on the preceding convolution. With the spring shown in Figs. 5, 6 and 7 on the other hand, the degree of transverse resiliency is greatly increased since during compression the upper ends of the smaller convolutions enter the larger convolutions and therefore do not exhibit the undesired piling up effect of the former spring. In effect, therefore, a spring such as shown in Figs. 5, 6 and 7 possesses substantially the same transverse resiliency as the spring of application Serial No. 284,722 but has twice the number of convolutions per unit length, thus providing a more nearly continuous upper supporting surface.

Referring to Fig. 8, the spring of Figs. 5, 6 and 7 is shown as applied to a roll periphery such as used in laundry machines. The roll proper comprises a base plate 9 which is

profusely perforated, as represented by the numerals 10 to provide a free passage for steam and water vapor to the interior of the roll. The direction of rotation of the roll is represented by the arrow and it will be noted that the inclined spring is mounted on the roll so that the convolutions slant in a direction opposite to that of the rolls' rotation. In this respect the roll of Fig. 8 is similar to that disclosed in application Serial No. 245,180 referred to hereinabove. However, in the present embodiment, it is preferred to compose the resilient surface of a plurality of separate springs wrapped around the exterior of the base 9 instead of providing a single helically wrapped spring. In addition, in order to prevent creep of the springs over the base 9 as the roll is rotated, tabs 11 are suitably struck up from said base to provide slightly hooked prongs for engaging the lower lengths of the spring convolutions. The number of these tabs may be determined in accordance with the size of the spring and the maximum working pressure 25 to be exerted on the roll.

As shown in Fig. 8, the spring supports a series of fabric coverings comprising an inner covering of duck or canvas 12 which is given substantially two complete turns 30 around the springs' periphery, and overlapping the last half turn of the canvas is a layer of wool material 13'. On top of this latter layer is the usual outer layer of muslin. If the duck covering 12 is fastened to 35 the outer surface of the spring padding or if it is fastened to the roll 9 by tapes, strips or the like, as the duck is wrapped tighter and tighter by revolving against the heated ironing chest, a portion of the padding in the neighborhood of the fastening means will 40 be locally compressed. This local compression will appear as a longitudinal depression in the surface of the roll and will mark the goods being ironed. For the purpose of 45 properly anchoring the fabric covering to the roll so that the inward radial component of the pull resulting from the continual winding effect may not be transmitted to the springs, the inner end of the canvas covering 50 13, is fastened as shown in Fig. 9, by means of eyelets 14 which are coupled to corresponding eyelets formed in looped spring members 15. As shown clearly in Figs. 9 and 10, the forward end of each member 55 15 is offset and registers with a corresponding narrow embossed or raised portion 16 in the surface of base 9, while the backward end of the member 15 is slightly curved and rests upon the outer surface of the base 9. Thus 60 the fabric coverings may be held against the spring covering without the use of permanent fastenings to either the springs or the base plate since the members 15 are readily placed in position without the use of bolts or other fastening means. With this man-

ner of fastening, as the roll rotates, there is a tendency to increase the tightness of the fabric coverings. However, since the covering is in effect resiliently attached to the base 9 the compression due to this winding effect 70 is not transmitted to the springs, as would be the case if the fabric coverings were attached directly thereto.

Any manner of uniting the free ends of the spring padding may be employed. However, it is preferred to employ a cap union such as illustrated in Fig. 10 wherein opposite ends of each spring on being wrapped around the roll are rigidly clamped together by means of a metal cap 17, which has its edges pinched 75 together as shown in Fig. 11.

Referring to Fig. 12 there is shown a novel method of attaching a series of fabric coverings whereby the winding effect on the coverings is relieved during substantially 80 one-half of each revolution of the roll. As shown in Fig. 12 the roll 9 is provided with duck or canvas covering for the spring padding which is preferably the same type of padding as disclosed in Figs. 8 and 9. For 85 the purpose of simplifying the drawing, however, the spring padding is omitted from Fig. 12. Instead of providing a single length of duck covering which is given two turns 90 around the roll as described in connection with Fig. 8, the duck covering is divided into two lengths 12^a and 12^b each of which goes around the roll once, and fastened at diametrically opposite points to the roll by means of 95 elements 15 as described hereinabove. A heated ironing chest C is shown in cooperative 100 relation with a portion of the roll surface. By means of the two part covering as shown in Fig. 12, the greater portion of the spring padding, which at any given instant is out 105 of registry with the steam chest, is allowed to expand. For example, assume that the roll is rotating in the direction of the arrow, the spring padding in the arc f is free to expand and the wrapper 12^b can slacken over 110 the wrapper 12^a in the rest of its periphery. The wrapper 12^a is, of course, being held tight from the point where it is fastened to member 15 to the far edge of the chest C. However, when the free end of wrapper 12^a leaves 115 the chest, the said wrapper can slacken and also the last quarter turn of wrapper 12^b. Thus the progressive and increasing tightening which occurs when a single length of duck 120 is employed, is avoided.

What I claim is:

1. In combination, a base plate, a spring padding mounted on said base plate, a fabric covering for said padding, and means for attaching said covering to said base plate, comprising a spring member attached at one end to said base plate and extending outwardly to a point of attachment with said covering substantially in circumferential alignment with the periphery of said padding.

2. In combination, a base plate, a spring padding mounted on said base plate, a fabric covering for said padding, and means for attaching said covering to said base plate, comprising a spring member attached at one end to said base plate and extending outwardly through said spring padding to a point of attachment with said covering substantially in circumferential alignment with the periphery of said padding.

3. In combination, a cylindrical base plate, resilient padding mounted circumferentially on said base plate, a fabric covering wrapped about said padding and disposed wholly upon the exterior thereof, and means for securing the inner end of said covering to said base plate, said means being resilient to enable its point of attachment with said covering to follow any local distortion of said padding.

4. In combination, a cylindrical base plate, resilient padding mounted circumferentially on said base plate, a fabric covering wrapped about said padding, and means for securing the inner end of said covering to said base plate, said means being resilient to enable its point of attachment with said covering to follow any local distortion of said padding.

5. In combination, a cylindrical base plate, a fabric covering for said base plate, means for resiliently supporting said covering in spaced relation to said plate, and a plurality of spring members interposed between the periphery of said base plate and an end of said covering for resiliently anchoring said covering to said base plate.

6. In combination, a cylindrical base plate, a fabric covering wrapped at least once about said base plate, means for resiliently supporting said covering in spaced relation to said base plate, and a plurality of spring members interposed between the periphery of said base plate and an inner end of said covering for resiliently anchoring said covering to said base plate.

7. In combination, a cylindrical base plate, a fabric covering for said plate, means for resiliently supporting said covering in spaced relation to said plate, and an angularly bent spring fastener interposed between said base plate and said covering and having one leg secured to said base plate, another leg movably supported upon the surface of said plate and secured to said covering at the point where said legs meet.

8. In a laundry ironing roll, the combination of a cylindrical base plate, a resilient padding mounted on said base plate, a fabric covering for said padding, and means for anchoring said covering to said plate, including a plurality of resilient strips each having one end attached to the base plate and the other end thereof attached to an end of the fabric and adapted to hold said end in spaced relation to said base plate.

9. In a resiliently padded roll, means for

70 preventing the progressive wrapping tighter of the fabric covering including a first length of fabric resiliently anchored at its inner end in spaced relation to said roll, another length of fabric resiliently anchored at its inner end in spaced relation to the roll at a point circumferentially spaced from the anchoring point for the first length, said pieces of fabric being of sufficient length to overlap and provide a double thickness covering throughout the periphery of said roll.

75 10. In a laundry ironing roll the combination of a cylindrical base, a resilient padding mounted on said base, a length of fabric covering wrapped around said padding and resiliently anchored at its inner end to said plate, another length of fabric having its inner end resiliently attached to said base at a point opposite to the anchoring point of the first length.

80 11. In a laundry roll, the combination of a cylindrical base, a resilient padding mounted on said base, a plurality of lengths of fabric covering for said padding, resilient means for anchoring said lengths to said plate at opposite sides thereof.

85 12. In a resiliently padded roll, means for preventing the progressive wrapping tighter of the fabric covering including a first length of fabric, resilient means for anchoring the inner end of said fabric to said roll, another length of fabric, resilient means for anchoring the inner end of said other length of fabric to the roll at a point circumferentially spaced from the anchoring point for the first length, said pieces of fabric being of sufficient length to overlap and provide a double thickness covering throughout the periphery of said roll.

90 105 In testimony whereof, I have signed my name to this specification this 30th day of September, 1929.

ARTHUR H. ADAMS.
